UNITED STATES PATENT OFFICE.

HENRY W. HARVEY, OF PROVIDENCE, RHODE ISLAND.

DESIGN FOR A BADGE.

SPECIFICATION forming part of Design No. 25,824, dated July 21, 1896.

Application filed March 4, 1896. Serial No. 581,858. Term of patent 3½ years.

To all whom it may concern:

Be it known that I, HENRY W. HARVEY, a citizen of the United States, residing at Providence, in the county of Providence and State 5 of Rhode Island, have invented and produced a new and original Design for Badges, of which the following is a specification, reference being had to the accompanying drawing, forming part thereof.

- 10 o The drawing is a front view of a badge, showing my design.

The leading feature of my design consists in the oval border inclosed in a wreath surrounding the representation of a stag's head, 15 15 the representation of an eagle above the wreath, and the two flags, one on each side of the eagle.

In the drawing the wreath 3 extends upward from the bow 4, representing a ribbon 20 tied in a bow-knot. The band 5 incloses the

oval space 6, in the lower part of which is the head of a stag 7 with the outer ends of the antlers extending over the band 5. The wreath is surmounted by the representation of an eagle 8. On each side of the eagle the representations of flags 9 9 project beyond the wreath 3. The wreath 3, the stag-head 7, and eagle 8 are in flat relief. 25

Having thus described my invention, I claim as new and desire to secure by Letters 30 Patent—

The design for a badge herein shown and described.

In witness whereof I have hereunto set my hand.

HENRY W. HARVEY.
